UNITED STATES PATENT OFFICE.

OSCAR BOTO SCHELLBERG, OF NEW YORK, N. Y.

PORTABLE APPARATUS FOR USE IN PROCTOTHERAPY.

Application filed June 27, 1925. Serial No. 40,046.

To all whom it may concern:

Be it known that I, OSCAR BOTO SCHELLBERG, a citizen of the United States, and a resident of New York city, county and State of New York, have invented certain new and useful Improvements in Portable Apparatus for Use in Proctotherapy, of which the following is a full, clear, and exact description.

10 Among the principal objects which the present invention has in view are: to provide a portable apparatus arranged to provide supports in grouped relation of receptacles for flushing and mitigating materials; and to provide a system of piping suitably connected to said receptacles to control the flow therefrom to a point of delivery, and the return from the point of delivery to the repository receptacle.

20

Drawings.

Figure 1 is a side view of an apparatus of the character mentioned, constructed and arranged in accordance with the present invention;

Figure 2 is a detail view showing the supporting frame for controlling the flushing and medicinal containers;

Figure 3 is a detail view on enlarged scale showing the method of assembling the flask supporting frame;

Figure 4 is a detail view on enlarged scale, showing the method of uniting the stand frame and the leg supports;

Figure 5 is a detail view on enlarged scale, and partly in section, showing the controlling valve structure for the dispensing pipes;

Figure 6 is a detail view showing a side elevation of a bracket member for holding the dispensing pipe and valves connected therewith in secured cooperative relation;

Figure 7 is a detail view in cross section of a cover with which the flushing and medicating flasks are provided.

45 As seen in the drawings, the flasks 11 and 12 are held in juxtaposed relation by a bracket frame 13, which partially surrounds the flask 12, and is secured on the uprights 14 by set screws 15. By means of the structure 50 employing the set screw 15, the flask 12 is adjusted optionally with relation to the flask 11.

The flask 11 is supported by a frame embodying the uprights 14 and the ring 16. 55 Both flasks have removable covers 17, each cover being provided as seen best in Figure

7, with a spring clip 18, which extend over in holding relation to the lip 19 of either of the flasks. It will be understood that one or more clips 18 may be employed.

60 The covers 17 are provided each with a filling funnel 20, a thermometer 21, and electric light 22. The light 22 is preferably of the tubular type, and serves the double function of providing light and heat within 65 the flushing and medicating contents of the flasks 11 and 12.

The flasks 11 and 12 are operatively connected with the three-way valve 23 by means of the pipes 24 and 25 respectively. The 70 pipes 24 and 25 are preferably constructed from rubber and are connected each with one of the branches of the U-shaped valve members 26. These members are provided with separate valves 27, and lead to the common 75 passage 28 which connects to the valve 23 when screwed or otherwise fastened thereto. Leading from the valve 23 are pipes 29 and 30, the former, as seen best in Figure 1 of the drawings, being connected with a flexible 80 applicator tube 31. This tube and its construction and employment are best set forth in Patent No. 1,425,420, dated August 8, 1922, granted to me for improvements in medical apparatus for use in proctotherapy. 85

By means of this tube, extremely high irrigations are performed, and applications of medicament are made therethrough. The tube is also used for drainage, when the contents of the intestines is delivered through 90 the pipe 29 to the pipe 30 and thence to a receptacle such as indicated by the numeral 32 in the drawings.

Whether the flushing fluid or the medicament shall be permitted to flow through the 95 pipe 29 to the applicator tube 31, or the contents of the intestines shall flow back through the pipe 29 to the pipe 30 is regulated and controlled by the three-way valve member 33, which member is freely controlled by the operator employing for that purpose the handle 34.

A feature of importance in the present invention is the portability of the apparatus, and to this end it will be noted the ring 105 frame 35 is provided with short extensions 36 that are socketed and capped to provide threads for registering with the threads of the threaded end 37 of the plug 38. The plug 38 fills and is rigidly attached to the hollow tubular leg 39 of the 110 tripod support for the flasks.

The tripod is composed of legs each having the tubular portion 39 provided with bayonet slots 40 that holdingly engage a short-leg section 41 having at the extremity 5 thereof a suitable caster roller 42.

From the foregoing it will be seen that when it is desired to transport the apparatus the supporting frame for the flasks may be removed from the ring frame 35, the 10 flasks themselves being lifted from the ring 16 and frame 13 respectively. Also the frame 13 may be removed from the uprights 14 by loosening the set screws 15, and the legs may be removed from the ring frame 15 35 by unscrewing the same from the extensions 36 thereof, and the legs may be divided into their half sections by removing the sections 41 from the legs 39.

When the bracket member shown in Figure 6 of the drawings is employed, the valve 20 23 and the members associated therewith may be disposed to rest on the bed clothes or other support if so desired, without overturning or becoming entangled. To this 25 end a ring-like body 43 has a series of recesses 44 in which the various pipes 29, 30 and the extension having the passage 28 rest. From the ring body 43 is extended a series of radial arms 45 flush with the 30 bottom of the ring and alined with the recesses 44, the ends of which are up-turned to form rests 46 that support the valve member 33 and the pipe 30. The outspread 35 relation of the brackets 45 forms a substantial though skeleton frame for resting the

valve 33 and parts associated therewith thereon.

From the foregoing it will be seen that when desired the apparatus may be disassociated in parts and packed for transportation within small compass. 40

Claims.

1. An apparatus as characterized comprising a plurality of holding receptacle 45 flasks; a distribution system operatively connected therewith and embodying a series of flexible pipes, and a multi-ported distributing valve, and a supporting member 50 for said valve and parts associated therewith, said supporting member having a ring-like body with extended arms adapted to receive and hold said pipes and parts associated therewith.

2. In an apparatus as characterized having a plurality of receptacles and a distribution system operatively connected therewith embodying a series of flexible pipes connected with a multi-ported distributing valve having extensions leading from the 60 ports, the combination with the valve and connections, of a holder for said valve, said holder comprising a ring having a series of recesses for reception of the valve extensions, and a series of radial flat arms 65 secured to and extending from said ring, the ends of said arms being upturned and disposed in alinement with said recesses for supporting the extensions of said valve.

OSCAR BOTO SCHELLBERG.
